UNITED STATES PATENT OFFICE

ELSWORTH M. BRISTOL, OF OAKLAND, CALIFORNIA

DEVICE FOR MAINTAINING CLOSURES IN OPENED OR CLOSED POSITION

Application filed March 12, 1928. Serial No. 260,886.

This invention relates to hardware and particularly pertains to fixtures adapted to be fitted to doors or similar closures to latch them in either opened or closed position.

It is the principal object of the present invention to generally improve and simplify devices of the character referred to whereby to provide a simple and inexpensive fixture capable of effectively latching a door or similar closure in either opened or closed position.

In carrying out this object into practice I provide a lever pivoted to the door frame and connected to the door in a manner normally permitting relative movement between the door and lever. This relative movement is necessary to operate the door as the door and lever swing about differently located pivotal points. To latch the door in either opened or closed position I provide a pair of latches adapted to prevent relative movement between the door and lever when the door is in either opened or closed position. By preventing relative movement between the door and lever the door is effectively latched against movement.

One form which the invention may assume is exemplified in the following description and illustrated by way of example in the accompanying drawings, in which:

Fig. 1 is a view in plan section through a door showing a fixture embodying the preferred form of my invention connected therewith with the door latched in closed position.

Fig. 2 is a perspective view of my improved fixture as attached to a door and shown with the door latched in open position.

Fig. 3 is a similar view with the door latched in closed position.

Fig. 4 is a perspective view of the bracket which is used to connect the fixture to the door frame.

Referring more particularly to the accompanying drawings, 10 indicates an opening surrounded by a door frame 11 including the usual jamb 12. Mounted within the frame is a pair of doors 14 which are hinged to opposite sides of the frame so that they may open outwardly as indicated by the arrows in Fig. 1.

The present application is particularly

concerned with fixtures such as indicated by the numeral 15 which are capable of maintaining the doors in either opened or closed position. One fixture 15 is provided for each door and is located on the interior side of the door as illustrated. Although in the present instance I have disclosed the fixtures as applied to a pair of garage doors, I am aware that they can be used in connection with various other types of closures and I do not limit myself to the use herein specified.

Each fixture 15 includes a bracket 16 secured to the door jamb contiguous to the door and which is formed with a horizontally disposed lug 17 projecting therefrom. The fixture may be located at any desired point vertically of the door but I prefer that it be located substantially centrally thereof. A flat horizontally disposed lever 18 is pivotally connected at its inner end to the lug 17 of the bracket 16. This lever 18 lies substantially parallel to the interior face of the door as illustrated and it is formed with a longitudinal slot 19. This slot 19 extends from a point short of the outer end of the lever to a point short of its inner end and is engaged by a vertical pin 20 carried by a bracket 21 which is suitably secured to the interior surface of the door.

The connection described between the lever 18 and the door permits the door under normal condition to be swung to either opened or closed position. When the door is swung on its hinges, the lever and door swing in unison but through different arcs due to the fact that the door and lever pivot about differently located pivotal points. Therefore, when the door swings on its hinges the pin 20 must travel in the slot 19 to accommodate the difference in arcs through which the door and lever 18 swing.

To latch the door in either opened or closed position I provide latches on the door to latch the lever to the door to prevent relative movement between the door and lever. By preventing relative movement between the door and lever, the door will be effectively latched.

The latch for holding the door in opened position is indicated by the numeral 22 and

comprises a bearing member 23 suitably secured to the door just above the lever. A keeper member 24 is pivoted to the bearing 23 for vertical swinging movement. This keeper is adapted to engage the outer edge of the lever when the door is swung to open position and is adapted to prevent relative movement between the door and lever. When it is desired to release the door, the keeper 24 is swung upwardly about its pivotal point to release the lever and the door may then be closed.

To latch the door in closed position I provide a second latch or that indicated in the drawings by numeral 25. This latch 25 includes a bracket 26 secured to the interior surface of the door and a keeper 27 pivotally connected to the bracket 26 for horizontal swinging movement. This keeper 27 has a pair of upturned keeper lugs 28 thereon adapted to engage opposite sides of the outer end of the lever as shown in Figs. 1 and 3. Such engagement prevents relative swinging movement between the door and lever and effectively latches the door closed.

The construction shown in the drawings permits the door to be opened ninety degrees but if it is desired to have the door opened further than this it is only necessary to change the point of pivotal connection between the lever 18 and the lug 17. For this purpose the lug 17 is provided with two spaced openings 29 adapted to receive a pivot pin so that the lever 18 may be connected to one of two differently located points on the lug 17.

In operation of the device it is constructed as illustrated in the drawings and assembled on a door and frame. When the door is in closed position the latch 25 may be operated to engage the outer end of the lever 18 and secure the door in closed position. When it is desired to open the door, the latch 25 is released and the door is swung to its open position. When it reaches its open position the keeper 24 of the latch 22 will engage the outer edge of the lever 18 and latch the door in opened position. This latch may be released by merely disengaging the keeper 24 from the lever.

From the foregoing it is obvious that I have provided a simple and efficient fixture of inexpensive manufacture for maintaining closures in opened or closed position.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. In combination with an outwardly swinging door and its frame, a horizontally

disposed lever arranged at the interior side of the door and pivotally connected at one end to the door jamb adjacent the hinged edge of the door, said lever being longitudinally slotted, means on the door slidably and pivotally engaging said slot whereby the door and lever may swing in unison but through different arcs, a pivotal keeper carried by the door and capable of detachable engagement with the end of the lever when the door is closed to prevent relative movement between the door and lever and thus latch the door in closed position, and a second pivotal keeper carried by the door and capable of detachable engagement with the lever when the door is in opened position to prevent relative movement between the door and lever and thereby latch the door in opened position.

2. In combination with a swinging door and its frame, a fixture adapted to hold a door in either open or closed position, said fixture comprising a bracket secured to the door frame contiguous to the hinged edge of the door and having an outwardly disposed lug, a flat horizontally disposed lever lying with its plane surface at right angles to the surface of the door and pivotally connected at one end to the lug, said lever having a longitudinal slot therein, said lever lying substantially parallel to the interior face of the door, a bracket secured to the door and having a vertical pin slidably and rotatably engaging said slot whereby the door may normally swing with the pin travelling in said slot to accommodate the different swinging arcs of the lever and door, a vertically pivotal keeper secured to the door intermediate the two brackets and capable of detachably engaging the lever when the door is in open position to latch the lever to the door and thus prevent relative movement between the same and hold the door in open position, a second keeper pivoted to the door horizontal swinging movement, said keeper being adapted to be swung to a position engaging the end of the lever when the door is in closed position to prevent relative movement between the door and lever and thus maintain the door in closed position.
